UNITED STATES PATENT OFFICE.

ALBERT W. HULL, OF SCHENECTADY, NEW YORK, ASSIGNOR TO GENERAL ELECTRIC COMPANY, A CORPORATION OF NEW YORK.

AMPLIFIER.

Application filed October 13, 1921. Serial No. 507,478.

To all whom it may concern:

Be it known that I, ALBERT W. HULL, a citizen of the United States, residing at Schenectady, in the county of Schenectady, State of New York, have invented certain new and useful Improvements in Amplifiers, of which the following is a specification.

My present invention relates to amplifiers, and more particularly to amplifiers of the multi-stage type employing a plurality of electron discharge devices connected in cascade.

One of the objects of my invention is to provide a simple and efficient circuit connection for connecting a plurality of electron discharge amplifiers in cascade.

Another object of my invention is to provide a multi-stage amplifier capable of giving a high degree of amplification for each stage and at the same time capable of operating with substantially the same efficiency for all frequencies.

In connecting electron discharge amplifiers in cascade in the past it has not been customary to operate the grids of the amplifiers at the same potential as the anodes of the preceding amplifiers of the series, the connection between stages having been made either by inductive or capacity coupling, or where a direct resistance connection has been made between stages it usually has been found necessary to employ a battery in the connection between the anode and the grid of the next succeeding amplifier of the series. In some cases where a direct connection has been made without a battery it has been necessary to employ separate filament and plate batteries for the different amplifiers.

A further object of my invention is to provide means whereby a direct conductive connection may be made from the anode of one amplifier to the grid of the next so that both electrodes will always be at the same potential and at the same time a common filament battery and a common plate battery may be employed for all of the amplifiers of the series.

The novel features which I believe to be characteristic of my invention are set forth with particularity in the appended claims. My invention itself, however, both as to its organization and method of operation, together with further objects and advantages thereof, will best be understood by reference

to the following description taken in connection with the accompanying drawing in which Fig. 1 illustrates diagrammatically one way whereby my invention may be carried into effect; Fig. 2 shows a modification and Fig. 3 is a characteristic curve showing the relation between grid voltage and grid current under one condition of operation.

I have indicated in the drawing a cascade connection of three electron discharge amplifiers, 1, 2 and 3, each having the usual electron emitting cathode 4, a discharge controlling grid 5 and an anode or plate electrode 6. In addition to these three electrodes these amplifiers may have an additional grid electrode 7 interposed between the grid 5 and anode 6. Current for heating the cathode of all of the amplifiers may be supplied by a common source 8. Current for the plate circuits of all of the amplifiers may be derived from a source connected to the supply mains 9 and 10 through filtering inductances 11 and capacities 12. The potential applied to the plate circuits of the amplifiers may if desired be varied by means of the variable connection 13 to the potentiometer 14. In most cases, however, the potentiometer may be omitted.

The currents to be amplified are impressed from conductors 15 and 16 upon the resistance 17, which is included in the grid circuit of amplifier 1. The amplified current in the plate circuit of amplifier 1 flows through the resistance 18 and corresponding amplified potential variations are produced upon the anode of amplifier 1. These potential variations of the anode of amplifier 1 are impressed upon the grid of amplifier 2 by means of the direct conductive electrical connection 19. Similarly, the amplified potential variations of the anode of amplifier 2 produced by the amplified current flowing through resistance 20 in the plate circuit are impressed by means of the direct conductive electrical connection 21 upon the grid of amplifier 3.

I have indicated in the plate circuit of amplifier 3 a telephone receiver 22 for giving an indication of the amplified current flowing in the plate circuit of amplifier 3 in case the current to be amplified is an audio frequency current. In case the current to be amplified is a radio frequency current, the plate circuit of amplifier 3 may be connected in any desired way with a detector. It will

be understood that as many amplifiers as desired may be connected in cascade and that any form of indicating apparatus desired may be associated with the plate circuit of the last amplifier of the series.

In the operation of multi-stage amplifiers in the past it has not been found feasible to operate the grid of one amplifier at the same potential as the plate of the preceding amplifier unless separate plate batteries were employed for the different amplifiers. This difficulty has been due to the fact that it has not been practical to operate the grid of the amplifier at a positive potential near that of the plate. Consequently where common plate batteries have been employed it has been found necessary to connect the plate of one amplifier to the grid of the next either by capacity or inductive coupling, or to insert a biasing battery in the grid circuit of the second amplifier. These disadvantages may, in accordance with my invention, be overcome in several ways to permit of the use of common plate and filament batteries for all of the amplifiers. If the resistance 18 is made of greater value than resistance 20, the drop of potential through resistance 18 will be greater than that through resistance 20, and the anode potential of amplifier 1 will be less than that of amplifier 2. Hence the grid of amplifier 2 may be connected to the anode of amplifier 1 and the positive potential of the grid amplifier 2 will always be less than the potential of the anode. Similarly the resistance of the plate circuit of amplifier 3 may be made less than that of 20 so that the plate potential of amplifier 3 will always be greater than the grid potential. By progressively decreasing the resistance in the plate circuits of the amplifiers in this way several more stages of amplifiers than those indicated may be operated in cascade for a common plate battery with the plate potential of each amplifier always higher than the grid potential.

One of the factors which has prevented the successful operation of amplifiers in cascade with the grid operating at about the same potential as the plate, has been the tendency of the grid to receive current from the plate due to the emission of secondary or impact electrons from the plate which flow to the grid preventing the grid from becoming more positive. This tendency may be overcome and the grids operated normally at about the same potential as the plate by making the plate in such a way that it will not emit any appreciable number of secondary electrons. This may be accomplished in several ways, as for example, by making the plate with a black or rough surface or by forming relatively deep and narrow corrugations on its surface. By constructing the plate in such a manner any impact electrons emitted will have difficulty

in escaping from the plate and reaching the grid.

By the use of the extra grid electrode 7, other operating advantages may be secured. In the drawing I have indicated the electrodes 7 of all of the amplifiers as connected directly to the positive terminal of the source which supplies current to the plate circuits. It will be apparent that by this connection the potential of electrodes 7 will be fixed at a positive value which is always higher than that of the anodes 6, whether the potentiometer 14 is used or omitted. If this potential and the potentials of the anodes are properly chosen advantage may be taken of secondary or impact emission from the anode to produce a high positive resistance or a negative resistance in the plate circuits in accordance with the well known dynatron action, as described in my Patent 1,387,984 of August 16, 1921. The negative resistance may be proportioned to neutralize the positive resistance in the plate circuit and the positive resistance of the grid circuit of the next succeeding amplifier, and thus greatly increase the degree of amplification per stage which may be obtained. A great increase in amplification over that obtainable without the electrode 7 may be obtained however without the resistances being actually negative provided they are increased from their normal low values to very high positive values. If desired, the connections to the grid 5 and 7 may be reversed, the grid 5 being maintained at the constant positive potential and the grid 7 serving as a control grid. In this way the grid 7 may be made to have a negative or very high positive resistance.

The capacity effect between grid and anode of a three-electrode device also greatly reduces the possible amplification of the device when radio frequencies are employed and causes a tendency for the device to produce undesired high frequency oscillations. Both of these difficulties may also be reduced by the use of the extra electrode 7, which serves as a screen between grid and anode either when maintained at a higher potential than the anode, as indicated in the drawing, or at approximately the same potential, or at a lower potential than the anode, as set forth more fully and claimed in my co-pending application, Serial No. 431,746, filed December 18, 1920.

In case the resistance of the grid circuits of the amplifiers becomes negative or of a higher positive value by reason of the emission of impact electrons from the grids, it may be desirable to insert positive resistances 23 in the connections 19 and 21, as indicated in Fig. 2. In this case the grids will operate at a lower potential than the anodes. This would reduce the amplification if the grids had normal positive resist-

ance characteristics, but if the grids have negative or approximately infinite resistance characteristics over the operating range the amplification will not be reduced. Under 5 these circumstances it would be possible to operate as many three-electrode amplifiers as desired in cascade with the grid of each amplifier operating at a lower potential than the anode.

10 The characteristic curve of Fig. 3 represents a grid current characteristic of very high positive resistance between the points *a* and *b*. If such a grid is connected by a high resistance 23 to an anode at a higher potential any postential variations produced on the anode will be impressed upon the grid with only slight diminution. For example, 15 if the potential changes of the anode are such that the grid potential tends to increase from *a* to *b*, the current through the resistance 23 will increase by only a small amount much less than the relative increase of potential, and the increased drop of potential through resistance 23 will be correspond- 20 ingly small.

25 What I claim as new and desire to secure by Letters Patent of the United States, is:—

1. Means for amplifying electric currents comprising a plurality of electron discharge devices each having a cathode, an anode and a pair of grid electrodes interposed between cathode and anode, means for impressing the currents to be amplified between the cathode and one of the grids of one of said devices, a source of potential connected between the cathode and anode of said device, means for impressing upon the second grid of said device a higher positive potential than that impressed upon the anode, and a direct conductive electrical connection between the anode of the first device and one of the grids of a second device.

2. Means for amplifying electric currents comprising a plurality of electron discharge devices each having a cathode, an anode and a pair of grid electrodes interposed between cathode and anode, means for impressing currents to be amplified between the cathode and one of the grids of one of said devices, a source of potential connected between the cathode and anode of said device, a high ohmic resistance in a circuit between the cathode and anode of said device which includes said source of potential, means for impressing upon the second grid of said device a higher positive potential than that impressed upon the anode, and a direct conductive electrical connection between the anode of the first device and one of the grids of a second device.

3. Means for amplifying electric currents comprising a plurality of electron discharge devices each having a cathode, an anode and a pair of grid electrodes interposed between cathode and anode, means for impressing

the currents to be amplified between the cathode and one of the grids of one of said devices, a source of potential connected between the cathode and anode of said device, means for impressing upon the second grid of said device a higher positive potential than that impressed upon the anode, and means for directly impressing between the cathode and one of the grids of a second device potential variations produced between the cathode and anode of the first device.

4. Means for amplifying electric currents comprising a plurality of electron discharge devices each having a cathode, an anode and a pair of grid electrodes interposed between cathode and anode, means for impressing currents to be amplified between the cathode and one of the grids of one of said devices, a source of potential connected between the cathode and anode of said device, a high ohmic resistance in a circuit between the cathode and anode of said device which includes said source of potential, means for impressing upon the second grid of said device a higher positive potential than that impressed upon the anode, and means for directly impressing between the cathode and one of the grids of a second device potential variations produced between the cathode and anode of the first device.

5. Means for amplifying electric currents comprising a plurality of electron discharge devices each having a cathode, an anode and a pair of grid electrodes interposed between cathode and anode, means for impressing the currents to be amplified between the cathode and the grid of said device which is nearest the cathode, a source of potential connected between the cathode and anode of said device, means for impressing upon the second grid of said device a higher positive potential than that impressed upon the anode, and a direct conductive electrical connection between the anode of the first device and one of the grids of a second device.

6. Means for amplifying electric currents comprising a plurality of electron discharge devices each having a cathode, an anode and a pair of grid electrodes interposed between cathode and anode, means for impressing currents to be amplified between the cathode and the grid of said device which is nearest the cathode, a source of potential connected between the cathode and anode of said device, a high ohmic resistance in a circuit between the cathode and anode of said device which includes said source of potential, means for impressing upon the second grid of said device a higher positive potential than that impressed upon the anode, and a direct conductive electrical connection between the anode of the first device and one of the grids of a second device.

7. Means for amplifying electric currents comprising a plurality of electron discharge

devices each having a cathode, an anode and a pair of grid electrodes interposed between cathode and anode, means for impressing the currents to be amplified between the cathode and the grid of said device which is nearest the cathode, a source of potential connected between the cathode and anode of said device, means for impressing upon the second grid of said device a higher positive potential than that impressed upon the anode, and means for directly impressing between the cathode and one of the grids of a second device potential variations produced between the cathode and anode of the first device.

8. Means for amplifying electric currents comprising a plurality of electron discharge devices each having a cathode, an anode and a pair of grid electrodes interposed between cathode and anode, means for impressing currents to be amplified between cathode and the grid of said device which is nearest the cathode, a source of potential connected between the cathode and anode of said device, a high ohmic resistance in a circuit between the cathode and anode of said device which includes said source of potential, means for impressing upon the second grid of said device a higher positive potential than that impressed upon the anode, and means for directly impressing between the cathode and one of the grids of a second device potential variations produced between the cathode and anode of the first device.

9. Means for amplifying electric currents comprising a plurality of electron discharge devices each having a cathode, an anode and a pair of grid electrodes interposed between cathode and anode, means for impressing the currents to be amplified between the cathode and one of the grids of one of said devices, a source of potential connected between the cathode and anode of said device, means for impressing upon the second grid of said device a higher positive potential than that impressed upon the anode, the potentials impressed upon the anode and second grid being so chosen that the device has a negative resistance in the circuit between cathode and anode, and a direct conductive electrical connection between the anode of the first device and one of the grids of a second device.

10. Means for amplifying electric currents comprising a plurality of electron discharge devices each having a cathode, an anode and a pair of grid electrodes interposed between cathode and anode, means for impressing currents to be amplified between cathode and one of the grids of one of said devices, a source of potential connected between the cathode and anode of said device, a high ohmic resistance in a circuit between the cathode and anode of said device which includes said source of potential, means for

impressing upon the second grid of said device a higher positive potential than that impressed upon the anode, the potentials impressed upon the anode and second grid being so chosen that the device has a negative resistance in the circuit between cathode and anode, and a direct conductive electrical connection between the anode of the first device and one of the grids of a second device. 70 75

11. Means for amplifying electric currents comprising a plurality of electron discharge devices each having a cathode, an anode and a pair of grid electrodes interposed between cathode and anode, means for impressing the currents to be amplified between the cathode and one of the grids of one of said devices, a source of potential connected between the cathode and anode of said device, means for impressing upon the second grid of said device a higher positive potential than that impressed upon the anode, the potentials impressed upon the anode and second grid being so chosen that the device has a negative resistance in the circuit between cathode and anode, and means for directly impressing between the cathode and one of the grids of a second device potential variations produced between the cathode and anode of the first device. 80 85 90 95

12. Means for amplifying electric currents comprising a plurality of electron discharge devices each having a cathode, an anode and a pair of grid electrodes interposed between cathode and anode, means for impressing currents to be amplified between the cathode and one of the grids of one of said devices, a source of potential connected between the cathode and anode of said device, a high ohmic resistance in a circuit between the cathode and anode of said device which includes said source of potential, means for impressing upon the second grid of said device a higher positive potential than that impressed upon the anode, the potentials impressed upon the anode and second grid being so chosen that the device has a negative resistance in the circuit between cathode and anode, and means for directly impressing between the cathode and one of the grids of a second device potential variations produced between the cathode and anode of the first device. 100 105 110 115

13. The combination in an amplifying system of a plurality of electron discharge amplifiers connected in cascade each of which has a cathode, an anode and two grids and plate and grid circuits connected between said cathode and said anode and one of said grids respectively, means for impressing currents to be amplified upon the grid circuit of the first of said amplifiers, means for impressing upon the second grid of each of said amplifiers a higher positive potential than that impressed upon the 120 125 130

anodes, and a direct conductive electrical connection between the anode of each amplifier of the series except the last and the first grid of the succeeding amplifier.

5 14. The combination in an amplifying system of a plurality of electron discharge amplifiers connected in cascade each of which has a cathode, an anode and two grids and plate and grid circuits connected
10 between said cathode and said anode and one of said grids respectively, high ohmic resistances in each of the plate circuits except the last of the series, means for impressing currents to be amplified upon the
15 grid circuit of the first of said amplifiers, means for impressing upon the second grid of each of said amplifiers a higher positive potential than that impressed upon the anodes, and a direct conductive electrical
20 connection between the anode of each amplifier of the series except the last and the first grid of the succeeding amplifier.

15. The combination in an amplifying system of a plurality of electron discharge amplifiers connected in cascade, each of which has a cathode, an anode and two grids and plate and grid circuits connected between said cathode and said anode and one of said grids respectively, means for impressing currents to be amplified upon the grid circuit of the first of said amplifiers, means for impressing upon the second grid of each of said amplifiers a higher positive potential than that impressed upon the anodes, and means for impressing potential variations produced upon the anode of each amplifier except the last directly upon the grid of the next succeeding amplifier of the series.

40   16. The combination in an amplifying system of a plurality of electron discharge amplifiers connected in cascade, each of which has a cathode, an anode and two grids and plate and grid circuits connected between said cathode and said anode and one of said grids respectively, high ohmic resistances in each of the plate circuits except the last of the series, means for impressing currents to be amplified upon the 45 grid circuit of the first of said amplifiers, means for impressing upon the second grid of each of said amplifiers a higher positive potential than that impressed upon the anodes, and means for impressing potential 50 variations produced upon the anode of each amplifier except the last directly upon the 55 grid of the next succeeding amplifier of the series.

17. The combination in an amplifying system of a plurality of electron discharge amplifiers connected in cascade each of which has a cathode, an anode and two grids and plate and grid circuits connected between said cathode and said anode and one of said grids respectively, means for

impressing currents to be amplified upon the grid circuit of the first of said amplifiers, means for impressing upon the second grid of each of said amplifiers a higher positive potential than that impressed upon the anode, the potentials impressed upon the anode and second grid of each amplifier being so chosen that each amplifier has a negative resistance in the plate circuit, and a direct conductive electrical connection between the anode of each amplifier of the series except the last and the first grid of the succeeding amplifier.

18. The combination in an amplifying system of a plurality of electron discharge amplifiers connected in cascade each of which has a cathode, an anode and two grids and plate and grid circuits connected between said cathode and said anode and one of said grids respectively, high ohmic resistances in each of the plate circuits except the last of the series, means for impressing upon the second grid of each of said amplifiers a higher positive potential than that impressed upon the anode, the potentials impressed upon the anode and second grid of each amplifier being so chosen that each amplifier has a negative resistance in the plate circuit, and a direct conductive electrical connection between the anode of each amplifier of the series except the last and the first grid of the succeeding amplifier.

19. The combination in an amplifying system of a plurality of electron discharge amplifiers connected in cascade each of which has a cathode, an anode and two grids and plate and grid circuits connected between said cathode and said anode and one of said grids respectively, means for impressing currents to be amplified upon the grid circuit of the first of said amplifiers, means for impressing upon the second grid of each of said amplifiers a higher positive potential than that impressed upon the anode, the potentials impressed upon the anode and second grid of each amplifier being so chosen that each amplifier has a negative resistance in the plate circuit, and means for impressing potential variations produced upon the anode of each amplifier except the last directly upon the grid of the next succeeding amplifier of the series.

20. The combination in an amplifying system of a plurality of electron discharge amplifiers connected in cascade each of which has a cathode, an anode and two grids and plate and grid circuits connected between said cathode and said anode and one of said grids respectively, high ohmic resistances in each of the plate circuits except the last of the series, means for impressing currents to be amplified upon the grid circuit of the first of said amplifiers, means for impressing upon the second grid of each of said amplifiers a higher positive potential

- than that impressed upon the anode, the potentials impressed upon the anode and second grid of each amplifier being so chosen that each amplifier has a negative resistance 5 in the plate circuit, and means for impressing potential variations produced upon the anode of each amplifier except the last directly upon the grid of the next succeeding amplifier of the series.
- 10 21. Means for amplifying electric currents comprising a plurality of electron discharge devices connected in cascade, each having a cathode, an anode and a controlling grid, grid and plate circuits associated with 15 each of said devices, a common source of potential for the plate circuits of all of said devices, separate connections from said source to each device, means for impressing the currents to be amplified upon the grid 20 circuit of the first device, and means for maintaining the grid of each succeeding device at the same potential as the anode of the preceding device.
22. Means for amplifying electric currents comprising a plurality of electron discharge devices connected in cascade, each having a cathode, an anode and a controlling grid, grid and plate circuits associated with 25 each of said devices, a common source of potential for the plate circuits of all of said devices, separate resistances in the plate circuit of each device, means for impressing the currents to be amplified upon the grid 30 circuit of the first device, and means for maintaining the grid of each succeeding device at the same potential as the anode of the preceding device.
23. Means for amplifying electric currents comprising a plurality of electron discharge devices connected in cascade, each having a cathode, an anode and a controlling grid, grid and plate circuits associated with 35 each of said devices, a common source of potential for the plate circuits of all of said devices, separate resistances in the plate circuit of each device, the values of said resistances progressively decreasing from the first to the last of the series, means for impressing the currents to be amplified upon the grid circuit of the first device, and means for maintaining the grid of each succeeding device at the same potential as the anode of the preceding device.
24. Means for amplifying electric currents comprising a plurality of electron discharge devices each having a cathode, an anode and a pair of grid electrodes interposed between cathode and anode, means for impressing the currents to be amplified between the cathode and one of the grids of one 40 of said devices, a source of potential connected between the cathode and anode of said device, means for impressing a constant positive potential upon the second grid of said device, and a direct conductive electrical connection between the anode of each amplifier of the series except the last and the first grid of the succeeding amplifier.
- connection between the anode of the first device and one of the grids of a second device.
25. Means for amplifying electric currents comprising a plurality of electron discharge devices each having a cathode, an anode and a pair of grid electrodes interposed between cathode and anode, means for impressing the currents to be amplified between the cathode and the grid of said device which is nearest the cathode, a source 75 of potential connected between the cathode and anode of said device, means for impressing a constant positive potential upon the second grid of said device, and a direct conductive electrical connection between the anode of the first device and one of the grids of a second device.
26. The combination in an amplifying system of a plurality of electron discharge amplifiers connected in cascade each of 80 which has a cathode, an anode and two grids and plate and grid circuits connected between said cathode and said anode and one of said grids respectively, means for impressing currents to be amplified upon the 85 grid circuit of the first of said amplifiers, means for impressing a constant positive potential upon the second grid of each of said amplifiers, and a direct conductive electrical connection between the anode of each amplifier of the series except the last and the first grid of the succeeding amplifier.
27. The combination in an amplifying system of a plurality of electron discharge amplifiers connected in cascade each of 90 which has a cathode, an anode and two grids and plate and grid circuits connected between said cathode and said anode and one of said grids respectively, means for impressing currents to be amplified upon the grid circuit of the first of said amplifiers, means for impressing a constant positive potential upon the second grid of each of said amplifiers, and a direct conductive electrical connection between the anode of each amplifier of the series except the last and the first grid of the succeeding amplifier.
28. The combination in an amplifying system of a plurality of electron discharge amplifiers connected in cascade each of 95 which has a cathode, an anode and two grids and plate and grid circuits connected between said cathode and said anode and one of said grids respectively, means for normally maintaining the first grid of each succeeding device at the same potential as the anode of the preceding device.
29. The combination in an amplifying system of a plurality of electron discharge amplifiers connected in cascade each of 100 which has a cathode, an anode and two grids and plate and grid circuits connected between said cathode and said anode and one of said grids respectively, means for impressing currents to be amplified upon the grid circuit of the first of said amplifiers, means for impressing a constant positive potential upon the second grid of each of said amplifiers, and means for normally 105 maintaining the first grid of each succeeding device at the same potential as the anode of the preceding device.
30. The combination in an amplifying system of a plurality of electron discharge amplifiers connected in cascade each of 110 which has a cathode, an anode and two grids and plate and grid circuits connected between said cathode and said anode and one of said grids respectively, a common source of potential for the plate circuits of all of said devices, means for impressing currents to be amplified upon the grid circuit of the first of said amplifiers, means for impressing a constant positive potential upon the second grid of each of said amplifiers, and a direct conductive electrical connection between the anode of each amplifier of the series except the last and the first grid of the succeeding amplifier.

29. The combination in an amplifying system of a plurality of electron discharge amplifiers connected in cascade each of which has a cathode, an anode and two grids and plate and grid circuits connected between said cathode and said anode and one of said grids respectively, a common source of potential for the plate circuits of all of said devices, means for impressing currents to be amplified upon the grid circuit of the first of said amplifiers, means for impressing upon the second grid of each of said amplifiers a higher positive potential than that impressed upon the anode, the potentials impressed upon the anode and second grid of each amplifier being so chosen that each amplifier has a negative resistance in the plate circuit, a common source of potential for the plate circuits of all of said devices, and means for normally maintaining the grid of each succeeding device at the same potential as the anode of the preceding device. 65
30. The combination in an amplifying system of a plurality of electron discharge amplifiers connected in cascade each of which has a cathode, an anode and two grids and plate and grid circuits connected between said cathode and said anode and one of said grids respectively, a common source of potential for the plate circuits of all of said devices, means for impressing currents to be amplified upon the grid circuit of the first of said amplifiers, means for impressing upon the second grid of each of said amplifiers a higher positive potential than that impressed upon the anodes, the potentials impressed upon the anode and second grid of each amplifier being of such values as to produce a sufficient emission of impact electrons from the anode to substantially change the resistance characteristics of the plate circuit, and a direct conductive electrical connection between the anode of each amplifier of the series except the last and the first grid of the succeeding amplifier. 70
31. The combination in an amplifying system of a plurality of electron discharge amplifiers connected in cascade each of which has a cathode, an anode and two grids and plate and grid circuits connected between said cathode and said anode and one of said grids respectively, means for impressing currents to be amplified upon the grid circuit of the first of said amplifiers, means for impressing upon the second grid of each of said amplifiers a higher positive potential than that impressed upon the anode, the potentials impressed upon the anode and second grid of each amplifier being so chosen that each amplifier has a negative resistance in the plate circuit, a common source of potential for the plate circuits of all of said devices, and a direct conductive electrical connection between the anode of each amplifier of the series except the last and the first grid of the succeeding amplifier. 75
32. The combination in an amplifying system of a plurality of electron discharge amplifiers connected in cascade each of which has a cathode, an anode and two grids and plate and grid circuits connected between said cathode and said anode and one of said grids respectively, means for impressing currents to be amplified upon the grid circuit of the first of said amplifiers, means for impressing upon the second grid of each of said amplifiers a higher positive potential than that impressed upon the anode, the potentials impressed upon the anode and second grid of each amplifier being of such values as to produce a sufficient emission of impact electrons from the anode to substantially change the resistance characteristics of the plate circuit, and a direct conductive electrical connection between the anode of each amplifier of the series except the last and the first grid of the succeeding amplifier. 80
33. The combination in an amplifying system of a plurality of electron discharge amplifiers connected in cascade each of which has a cathode, an anode and two grids and plate and grid circuits connected between said cathode and said anode and one of said grids respectively, means for impressing currents to be amplified upon the grid circuit of the first of said amplifiers, means for impressing upon the second grid of each of said amplifiers a higher positive potential than that impressed upon the anodes, the potentials impressed upon the anode and second grid of each amplifier being of such values as to produce a sufficient emission of impact electrons from the anode to substantially change the resistance characteristics of the plate circuit, and a direct conductive electrical connection between the anode of each amplifier of the series except the last and the first grid of the succeeding amplifier. 85
34. Means for amplifying electric currents comprising a plurality of electron discharge devices connected in cascade, each having a cathode, an anode and a controlling grid, grid and plate circuits associated with each of said devices, a common source of potential for the plate circuits of all of said devices, means for impressing currents to be amplified upon the grid circuit of the first device and means for impressing upon the grid of each succeeding device potential variations produced upon the anode of the preceding device, the potentials of the anode and grid of each of the succeeding devices being of such values as to produce a sufficient emission of impact electrons from the grid to substantially change the resistance characteristic of the grid circuit. 90
- In witness whereof, I have hereunto set my hand this 10th day of October, 1921.
- ALBERT W. HULL. 100
